UNITED STATES PATENT OFFICE.

HERMAN F. HOLMQUEST, OF BROOKLYN, NEW YORK.

TWO-CYCLE EXPLOSIVE-ENGINE.

1,370,586.

Specification of Letters Patent. Patented Mar. 8, 1921.

Application filed October 22, 1919. Serial No. 332,455.

To all whom it may concern:

Be it known that I, HERMAN F. HOLMQUEST, a citizen of the United States, and resident of Brooklyn, in the county of Kings 5 and State of New York, have invented certain new and useful Improvements in Two-Cycle Explosive-Engines, of which the following is a specification.

This invention relates to internal combustion engines, and is particularly directed to the two-cycle type of engines, that have one explosion for each reciprocation of the piston.

One of the objects of the invention is to 15 provide improved means for compressing the charge or mixture in the rear end of the cylinder, and then causing such charge to enter the other end of the cylinder.

Another object of the invention is to provide in such a construction, improved arrangement of the valves for controlling the said charge.

In the accompanying drawing showing one embodiment of my invention, Figure 1 25 is a vertical section, partly in elevation.

Fig. 2 is a cross section on the line 2—2 of Fig. 1.

Fig. 3 is a cross section on the line 3—3 of Fig. 1.

As shown in the drawings, I provide a cylinder 2 having its upper end 3 closed, and provided with an inlet 4 that connects with a conduit 5, leading into the other end of the cylinder at the port 6. This lower end 35 of the cylinder is closed by an end wall 7 that contains the said outlet port 6, and an inlet port 8 for the mixture. The latter port connects by a short conduit 9 with a carburetor 10, of any desired form.

A trunk piston 11 slides in the cylinder, whose end wall 12 is shown as having an opening forming a valve seat 13, controlled by a valve 14, in the nature of a check-valve. This valve will open when the pressure in 45 side of the piston exceeds the pressure in the cylinder above the piston, but is otherwise held closed by its spring 15. The outlet port 6 for the lower portion of the cylinder is shown as controlled by a check-valve 16, 50 that will open by the pressure in the lower port of the cylinder, to admit the compressed charge to the conduit 5. The inlet port 4 for the upper part of the cylinder from the conduit 5, is shown as controlled 55 by a check-valve 17. This will prevent the charge in the cylinder above the piston from

passing back into the conduit 5 on the compression part of the stroke, when the piston is moving upward.

The inlet passage 8 for the cylinder is 60 controlled by a valve 18, whose stem 19 may be controlled by a valve lifting device, or this valve 18 may be a simple check-valve operated by its coil spring 20, to retain the valve seated when the piston compresses the 65 charge in the lower portion of the cylinder, but which will open on the suction stroke to admit the charge from the carburetor 10.

When the piston 11 is in its lowermost position, its head will expose openings 21 in 70 the cylinder that connect with an exhaust 22. But as soon as the piston rises a short distance it will close these exhaust openings. I further provide an annular flange 23 on the piston head a short distance inside of the 75 margin, that will serve to deflect the exhaust gas, and also the charge admitted by the inlet valve 14 to cause the charge to move upwardly at the central portion of the cylinder, while the exhaust gas will pass 80 downwardly around the outside of the cylinder to the exit.

The cylinder 2 is shown provided with an extension 24 connecting with a crank case 25, containing the usual crank 26 and connecting rod 27. A piston rod 28 extends downwardly from the piston 11 being secured thereto by wings 29; which piston rod connects with the crank by a cross head 30 suitably guided in the extension 24. At 40 90 is shown the usual spark plug.

Means are shown in the crank case for operating the inlet valve 18, comprising a cam 31 on the shaft 41 that will swing a lever 32 pivoted in the crank case at 33, and 95 hinged to the stem 19 of the valve 18. As indicated this cam will swing the lever and raise the valve 18, that will be seated by its spring 20 when the cam releases the lever 32. But it is to be understood that the lower 100 portion of the valve stem 19 can be disconnected, and the valve 18 with its spring 20 will operate as an ordinary check-valve.

In the operations of the engine, when the piston rises it will cause the valve 18 to be 105 opened, or such valve is opened at this time by the cam, and a charge will be drawn into the lower portion of the cylinder during the upward stroke of the piston. When the piston moves downwardly by the explosion of 110 a charge above it, the mixture in the lower part of the cylinder will be compressed and

will close the valve 18, unless previously closed by the cam control, that is properly so timed. This will cause the outlet valve 16 to open and the charge will pass into the cylinder 5 when a certain pressure has been reached. But the check valve 4 will not open until the exploded charge above the piston has driven the piston down and exposed the exhaust ports and a considerable portion of the exploded charge has escaped. This compressed mixture in the lower portion of the cylinder and in the conduit 5 will now open the check-valve 17 and pass into the upper portion of the cylinder above the piston. This will assist in driving out the exploded charge. At this time the check-valve 14 in the piston will also be raised by the excessive pressure in the cylinder below the piston, and a portion of the charge compressed in the cylinder below the piston will pass through the piston port at the central portion of the cylinder, that will also assist in driving out the exploded charge. But the piston will very shortly commence to rise and close the exhaust ports by the piston head, and this will cause a compression of this charge in the cylinder above the piston. This will result in the valve 17 at once closing, and also the valve 14 in the piston, so that during the entire upward stroke of the piston, after closing the ex-

haust ports, there will result a high degree of compression of this charge in the cylinder. When the piston reaches the top the spark plug will ignite this charge to drive the piston downwardly; and this will cause the compression of a new charge for the next cycle of operation, as has been set forth.

What I claim is:—

1. In a two cycle gas engine, the combination of a cylinder having a head, a piston sliding therein, a valve in the piston, a fuel supplying inlet port at the end of the cylinder remote from the head, an outlet port at said end, a valve controlling the outlet port, an inlet port at the head end of the cylinder, a valve controlling the inlet port, and a conduit connecting the inlet and outlet ports.

2. In a two cycle gas engine, the combination of a cylinder having a head and having the opposite end closed, a fuel supplying inlet port at the closed end of the cylinder, a conduit affording communication between the ends of the cylinder, a valve at each end of the conduit, a valve for the inlet port, a piston reciprocating in said cylinder, a valve in said piston, and mechanical means to control the valve of the inlet port.

Signed at New York city, N. Y., on October 18th, 1919.

HERMAN F. HOLMQUEST.
